UNITED STATES PATENT OFFICE.

WALTER M. SCHWARTZ AND ELWOOD B. AYRES, OF PHILADELPHIA, PENNSYLVANIA,
ASSIGNORS TO PROCTOR & SCHWARTZ, INCORPORATED, OF PHILADELPHIA, PENN-
SYLVANIA, A CORPORATION OF PENNSYLVANIA.

LEATHER DRIER.

Application filed January 7, 1922. Serial No. 527,588.

To all whom it may concern:

Be it known that we, WALTER M. SCHWARTZ and ELWOOD B. AYRES, citizens of the United States, residing in Philadelphia, 5 Pennsylvania, have invented certain Improvements in Leather Driers, of which the following is a specification.

One object of our invention is to design 10 an apparatus for drying leather so that a number of skins can be dried in a minimum of space.

A further object of the invention is to design the apparatus so that the skins to be dried can be arranged comparatively close 15 together in order that both sides of the skins may be subjected to the warm air in circulation.

A still further object of the invention is to provide frames on which the skins are 20 mounted so designed that two skins can be carried by a single frame and the frame can be withdrawn from the drying chamber so that the skins can be examined from time to time during the drying operation 25 and the dried skins removed and other skins substituted therefor without interfering with the drying operation.

In the accompanying drawings:

Fig. 1 is a side view of our improved 30 leather drying apparatus;

Fig. 2 is a plan view, partly in section;

Fig. 3 is an end view showing one of the frames withdrawn and another frame partly withdrawn;

Fig. 4 is a perspective view of a frame 35 in a vertical position ready to be admitted to the drier;

Fig. 5 is a detached perspective view of a frame in a horizontal position, in which 40 position a skin is attached to, or detached from, a frame;

Fig. 6 is an enlarged sectional view showing a series of frames within the drying chamber;

Figs. 7 and 8 are enlarged views showing 45 the method of attaching the skins to the carriers;

Fig. 9 is a view illustrating a modification of the arrangement for carrying the frames; 50 and

Fig. 10 is a view of a modification of the means for supporting the material to be dried on the frame.

Referring to the drawings, 1 is the cas-

ing of a drying apparatus. 2 is the drying chamber and 3 is the circulating chamber, which is situated above the drying chamber, and in which the fans 4 and heating coils 31 are located. The fans are located in openings in the horizontal partition 5.

6 are vertical partitions, which cause the air to circulate in the manner shown by arrows, Fig. 1. 7 is a driving shaft having belt wheels 8 thereon. Belts pass around these wheels and around wheels 9 on the vertical shafts 10. The method of driving the fans may be modified without departing from the essential features of the invention.

Each side wall of the drier has a series of vertical slots therein for the passage of the frames which carry the skins to be dried.

Extending transversely through the apparatus is a series of lower tracks 11 and 12, and upper tracks 13 and 14. The lower track 11 and the upper track 13 extend beyond one side of the drying chamber, as shown in Figs. 2 and 3. The other tracks 12 and 14, which are longitudinally arranged in respect to the tracks 11 and 13, project on the opposite side of the drying chamber. One series of tracks alternate with the other series and the tracks extend through the horizontal slots in the casing.

85 Arranged to travel on the track 11 is a series of narrow frames 15. Similar frames 16 are mounted on the rails of track 12 on the opposite side of the apparatus. Each frame has a lower member 17 and an upper 90 member 17^a. These two members are connected by vertical end members 18 and 19 which are of such width as to close the slots in the casing when the frames are in the casing or are withdrawn therefrom. The two members extend to, and are guided by, 95 the upper track 13. A handle 20 is provided so that the operator can readily withdraw a frame from the casing.

On the end members 18 and 19 of each frame are sockets 21 for the pivot pins 22 of a rectangular carrier 23. Within this carrier is a wire screen 24 of any mesh desired. Clamp plates 32 are secured to the wire screen 24 and are connected to the carrier by straps 33, as shown in Fig. 8.

100 The skins *a* are secured to the carrier on each side of the wire screen by clamps 25.

which are hooked into the screen, as shown in Fig. 7, and are so designed as to keep the skins free of the screen, as illustrated, so that air can circulate freely between the 5 two skins.

By mounting the carrier on pivots, it can be turned from the vertical to the horizontal position, as shown in Figs. 4 and 5. Links 26, pivoted to a frame at 27 and to 10 the rear vertical member at 28, retain a carrier in the horizontal position. It will be noticed that the carriers are pivoted off center for this purpose.

In Fig. 3, the frames 15 are shown provided with grooved wheels 29, which travel on the rails of the track 11. In some instances, the frames may be suspended from overhead rails, or trolleys 30, Fig. 9.

By making the frames on one side alternate with those on the opposite side, they 20 can be arranged close together and wide slots may be made in the casing for the passage of the frames, which can be closed by the wide end members of the frames.

25 Although the fans and heating pipes are illustrated as located in a particular position, it will be understood that they may be located in other positions without departing from the spirit of the invention.

30 The apparatus occupies very little space and will hold a large number of skins. The skins can be readily examined from time to time in order to ascertain whether they are drying properly. This is accomplished without interfering with the proper circulation 35 of air within the drying chamber.

While a carrier in the form of a wire screen is shown and described, it will be understood that a perforated metal screen may 40 be used, if desired, as shown in Fig. 10.

We claim:

1. The combination in a drying apparatus, of a drying chamber, said chamber having a series of vertical slots in each side wall 45 of the casing, the slots on one side alternating with those on the opposite side; a series of frames at each side arranged to enter the drying chamber through the slots; and means for supporting material to be dried on the 50 said frames.

2. The combination in drying apparatus, of a drying chamber; means for circulating air in said chamber, the side walls of the chamber being slotted, the slots on one side 55 alternating with those on the opposite side; a series of frames at each side of the apparatus; rails on which the frames travel, said

rails extending into the drying chamber; and a carrier mounted on each frame, said carrier supporting the material to be dried. 60

3. The combination in a drying apparatus, of a casing enclosing a drying chamber; a horizontal partition above the drying chamber; fan openings in said partition; circulating fans mounted in said openings; vertical partitions extending into the drying chamber from the horizontal partition, the casing of the drying chamber having a series of slots at each side, the slots on one side alternating with those on the opposite 70 side; and material-carrying frames at each side arranged to pass into the drying chamber through the slots in the side walls thereof.

4. The combination in a drying apparatus, of a casing enclosing a drying chamber and 75 a circulating chamber; fans for circulating air in the chambers; means for heating the air in circulation, each side wall of the drying chamber having vertical slots therein, the slots at one side alternating with those 80 on the opposite side; a series of upper and lower rails at each side of the apparatus, the rails extending through the slots in the casing; frames guided by the rails, the frames, when located within the drier, closing the 85 slots; and a carrier pivotally mounted on each frame, said carrier being provided with means by which a skin to be dried can be attached thereto.

5. The combination in a drying apparatus, 90 of a casing enclosing a drying chamber; means for circulating air in said chamber; a series of frames arranged to be located in the chamber, each frame having a carrier in the form of a screen; and clamps having hooks 95 engaging the screen, each clamp having a jaw for engaging the skin to be dried, the jaws of the clamps being so proportioned that the skins will be held clear of the wire screen when drying. 100

6. The combination in a drying apparatus, of a casing enclosing a drying chamber; means for heating the air; means for circulating said heated air; a series of narrow frames arranged to be located in the chamber, each frame having a carrier pivotally mounted thereon, the body of the carrier being in the form of a screen; and hooked clamps on each side of the screen arranged to engage skins to be dried, the skins being 110 so positioned that there will be a clear space between them for the circulation of air.

WALTER M. SCHWARTZ.
ELWOOD B. AYRES.
